UNITED STATES PATENT OFFICE.

OSCAR HERRMANN, OF NEW YORK, N. Y.

ELECTRIC ATTACHMENT FOR KEYBOARDS OF AUTOPLAYERS.

1,073,044.

Specification of Letters Patent.

Patent d Sept. 9, 1913.

Application filed May 13, 1912. Serial No. 696,961.

To all whom it may concern:

Be it known that I, OSCAR HERRMANN, a citizen of the United States, residing at New York, in the county of New York and State of New York, have invented a new and useful Electric Attachment for Keyboards of Autoplayers, of which the following is a specification.

This invention has reference to improvements in electric attachments for keyboards of auto-players and more particularly for auto-pianos whether of the self contained type or of any other type, and its object is to provide a device whereby other sounds may be produced than those due to the action of the strings of the piano to which the attachment is applied.

For convenience of description it will be assumed that the attachment is applied to the keyboard of a self playing piano and to this end it comprises a support or casing designed to be mounted over the keyboard in such manner that pins provided with electric contacts and carried by the casing will rest upon the keys of the keyboard. Each contact is connected up in normally open electric circuit which also includes a sound producing device capable of actuation by electric currents. Such sound producing devices are preferably electric bells properly tuned, so that when the keys move for the production of music by the piano such music is accompanied by appropriate bell tones, thus adding materially to the pleasing effect of the instrument. Of course, other electrically actuated sound reproducing devices than bells may be employed, but for convenience of description it will be considered that the electrically actuated devices are electric bells with the understanding that the term is to be interpreted as including other appropriate devices.

The invention will be best understood from a consideration of the following detailed description taken in connection with the accompanying drawings forming a part of this specification, with the further understanding that while the drawing shows a practical form of the invention it may assume other practical forms, wherefore the invention is not confined to any exact conformity with the showing of the drawings, but in the practical embodiment may be changed and modified over the showing of the drawings so long as such changes mark

no material departure from the salient features of the invention.

In the drawings: Figure 1 is a front elevation of so much of the keyboard of a self-playing instrument as is necessary for the understanding of the present invention with the attachment applied. Fig. 2 is a longitudinal vertical section through the attachment shown in Fig. 1 with the keyboard shown in elevation. Fig. 3 is a cross section of the structure shown in Figs. 1 and 2 but drawn to a larger scale and indicating a few bells as illustrative of the electrically actuated devices forming a part of the attachment.

Referring to the drawings there is shown a keyboard provided with the usual white keys 1 and black keys 2, and this keyboard may be taken as typical of any suitable keyboard for the purpose, since the keyboard and its details do not enter into the present invention. There is also provided a casing 3 which in the present instance is of substantially the length of the keyboard and may be of rectangular cross section, as indicated, or of any other suitable shape. At the ends of the casing 3 are projecting portions 4 adapted to uprights 5 which may be secured to the ends of the keyboard frame, and these uprights 5 have longitudinal slots 6 whereby through the use of suitable fastening devices 7 extending through the projections 4 and the slots 6 the casing 3 may be adjusted at proper height with relation to the keyboard.

Within the casing 3 is a longitudinal partition 8 at an appropriate distance above the bottom of the casing, which bottom is indicated at 9. The partition 8 and bottom 9 are provided with an appropriate number of matching passages 11, 12, respectively, for pins of which there are shown two series with the individual pins numbered 13 and 14, respectively. These pins are upright and between the partition 8 and bottom 9 are each provided with an enlargement 15 near the bottom 9, and between its enlargement 15 and the partition 8 the pin is surrounded by a spring 16 tending to project the pin through the bottom of the casing. Each pin also extends through a plate 17 by way of a passage 18 of such size that the pin will not come into engagement therewith except by way of the enlargement 15. Ordinarily the casing 3 is made of wood or other suitable

insulating material and the plate 17 is made of metal, so as to be conducting, while the pins 13 and 14, as well as the enlargements 15, are also of metal to be conducting, wherefore when the enlargement 15 enters the opening 18 in the plate 17 good electrical contact is thereby established, the enlargement 15 and passage 18 being shaped into conformity one with the other for such purpose.

The pins 13 are so disposed as to engage the tops of the keys 1, while the pins 14 are so disposed as to engage the tops of the keys 2, and the springs 16 are of such strength that they will yield sufficiently to permit the enlargements 15 to move away from the plate 17 when the pins 13 and 14 are in engagement with the respective keys, without causing depression of the keys, but these springs, when the keys are depressed, will act on the pins to move them until the enlargements 15 are in engagement with the plate 17. Each pin is connected by an electric conductor 19 to one side of a bell 20 which may be of the trembler or any other suitable type, while the other side of each bell is connected to a common conductor 21 in turn connected to one side of a battery 22, or other suitable source of electric energy. The other side of the battery is connected by a conductor 23 to the plate 17. However, whether the exact arrangement described for the electric circuits be followed or not, the circuits are so disposed that whenever an enlargement 15 is brought into contact with the plate 17 by the movement of a respective pin 13 or 14, an electric circuit is established from the battery or other source 22 to the plate 17, through pin 13 or 14, conductor 19 connected to said pin, the particular bell to which the conductor under consideration is connected, and from thence by way of the conductor 20 back to the battery, wherefore so long as the key controlling the pin under consideration is depressed the bell will sound.

The bells 20 are tuned in accordance with the keys to which they are connected, so that when the instrument is being played not only will the usual strings of the instrument emit sounds in accordance with the composition being rendered, but the bells will also emit corresponding sounds having bell tones, thus enhancing the pleasing effect produced upon the listener. Of course, the bells may be of the single stroke or trembler type as the manufacturer may desire, but in each instance they are electric bells or other sound-producing devices which require electro-magnets.

Since the exposed surface of each key 1 is usually covered by some hard substance, such as bone or ivory, that end of each pin 13 which engages a key 1 will engage it at 65 the hard surface and so needs no particu-

lar preparation, although it may be slightly rounded. However, the keys 2 usually have no such protection and consequently it is preferred to introduce a small wear plate 24 between the active end of a pin 14 and a corresponding key 2.

The casing 3 is usually made of sufficient internal size between the pins 14 and the back of the casing to accommodate all the conductors 19, which may be gathered together in the form of a cable 25 leading through the top or other portion of the casing near one end thereof and carried therefrom to the place where the bells 20 are disposed, which bells may be readily located at any convenient point on or in the casing of the main instrument, or at some place removed therefrom.

When it is not desired to have the bell accompaniments, the casing 3 with the parts carried thereby may be readily removed from the key board, or simply raised sufficiently to have the pins 13 and 14 clear of the keys. In such case a switch 26 located at any convenient point in the power circuit for the bells may be open, and the fact that the springs 16 have caused the enlargements 15 to engage plate 17 will have no effect upon the bells. The bells are connected up in the circuit in multiple so that any number of the bells may sound at one time in accordance with the keys which may be actively moved at a time.

What is claimed is:—

1. An attachment for the keyboards of keyed musical instruments comprising a suitable number of electrically responsive sound-producing means tuned to correspond to tones represented by respective keys of the instrument, a casing, a conducting strip 10 therein provided with passages through it, pins traversing the passages through the strip and projecting below the casing and each of a length to engage a respective key of the keyboard, each pin being provided with an enlargement adapted to the passage in the conducting strip through which the pin extends to make contact with said strip, and means for electrically connecting the strip to all the electrically responsive sound producing means, and each pin to a respective one of said sound producing means.

2. An attachment for keyboards of auto-players comprising a suitable number of electrically responsive sound-producing means tuned to correspond to tones represented by respective keys of the instrument, a casing provided with means for supporting it above the keyboard, said casing having a bottom member and a longitudinal partition above and spaced from the bottom member, with matching holes through the bottom member and partition, an electrically conducting plate on the bottom member having passages therethrough of greater size than

and matching the holes through the bottom member, pins extending through the matching holes in the bottom member and partition and each of a length to reach a respective key of the keyboard, an enlargement on each pin shaped to engage in a respective passage in the conducting plate and make electrical contact therewith, a spring around each pin between the enlargement and the partition, and electric conductors connecting the conducting plate to all the sound producing means and each pin to a respective sound producing means.

3. An attachment for keyboards of auto-
players comprising a suitable number of elec-
trically responsive sound producing means
tuned to correspond to tones represented by
respective keys of the instrument, a casing
provided with means for supporting it above
the keyboard, said casing having a bottom
member and a longitudinal partition above
and spaced from the bottom member, with
matching holes through the bottom member
and partition, an electrically conducting
plate on the bottom member having passages
therethrough of greater size than and
matching the holes through the bottom

member, pins extending through the match-
ing holes in the bottom member and parti-
tion and each of a length to reach a respec- 30
tive key of the keyboard, an enlargement on
each pin shaped to engage in a respective
passage in the conducting plate and make
electrical contact therewith, a spring around
each pin between the enlargement and the 35
partition, and electric conductors connecting
the conducting plate to all the sound-pro-
ducing means and each pin to a respective
sound-producing means, the pins in the cas-
ing being arranged in two rows at respec- 40
tively different distances from the front of
the casing, the pins of one row being of
greater length than those of the other to
cause the pins to engage the white and black
keys of an instrument provided with such a 45
keyboard.

In testimony, that I claim the foregoing
as my own, I have hereto affixed my signa-
ture in the presence of two witnesses.

OSCAR HERRMANN.
